UNITED STATES PATENT OFFICE

165,684

HAIR CURLING DEVICE

Frank G. Hall, Chicago, Ill.

Application August 21, 1951, Serial No. 16,396

Term of patent 7 years

(Cl. D86—8)

To all whom it may concern:

Be it known that, I, Frank G. Hall, a citizen of the United States, residing at Chicago, State of Illinois, have invented a new, original, and ornamental Design for a Hair Curling Device, of which the following is a specification, reference being had to the accompanying drawing, forming a part hereof.

I claim:

The ornamental design for a hair curling device, as shown.

FRANK G. HALL.
